ENGINE STARTER GEARING

Arthur R. Tobias, Elmira, N. Y., assignor to Bendix Aviation Corporation, a corporation of Delaware

Application October 17, 1951, Serial No. 251,679

6 Claims. (Cl. 74—7)

1

The present invention relates to engine starter gearing, and more particularly to that type of automatically engaging drive which incorporates means for preventing premature demesh of the drive pinion responsive to a false start of the engine.

Drives of this general type which employ a centrifugal latch for holding the pinion in mesh until the starting motor has attained a predetermined speed offer some advantages over those controlled in other ways, but as heretofore constructed have been somewhat subject to the disadvantage that if the operator opens the starting switch too soon after the engine starts, the motor may not reach the necessary speed to release the latch, and the pinion stays in mesh indefinitely while the engine is running.

It is an object of the present invention to provide a novel engine starter drive of the "anti-kickout" or "follow through" type in which the demesh of the starter pinion is controlled primarily by the speed of the starting motor while the pinion is overrunning, which incorporates supplemental means responsive to engine speed for securing demesh of the pinion.

Further objects and advantages will be apparent from the following description taken in connection with the accompanying drawing in which:

Fig. 1 is a side elevation partly broken away and in section of a preferred embodiment of the invention showing the parts in normal or idle position; and

Fig. 2 is a similar view showing the parts in the positions assumed when the starting pinion is overrunning the drive while held in mesh with the engine gear.

In Fig. 1 of the drawing there is illustrated a power shaft 1 on which a driving head 2 is fixedly mounted as by means of a cross pin 3. An anchor plate 4 is non-rotatably mounted on the drive head 2 against a shoulder 5 thereon, and is yieldably connected by a spring 6 with a similar anchor plate 7 non-rotatably mounted on the end of a screw shaft 8 against a shoulder 9. A control nut and driving overrunning clutch member 10 is threaded on the screw shaft 8, and is provided with clutch teeth 11 normally engaging similar overrunning clutch teeth 12 formed on a driven clutch member 13, which is splined on the extended hub 14 of a pinion 15, slidably journaled on the power shaft 1 for engagement with an engine gear 16.

The driven overrunning clutch member 13 is retained on the pinion 15 by a lock ring 17, and

2

a mesh-enforcing spring 18 yieldably holds the pinion in extended relation to said clutch member.

5 A barrel member 19, non-rotatably mounted on the control nut 10, surrounds and encloses the clutch members, which are retained in the barrel by a lock ring 21. A light clutch spring 22 is located between a shoulder 23 on the driven clutch member and a terminal flange 24 of the barrel so as to yieldingly hold the teeth 11, 12 of the overrunning clutch members in engagement.

10 For ease in assembly, the screw shaft 8 is preferably formed in two interlocking parts as illustrated, held together by a sleeve 20 suitably anchored in the driving head 2.

15 A latch member 25 is slidably mounted for radial movement in the driving clutch member 10, and is yieldably pressed into engagement with the threads of the screw shaft 8 by means of a spring 26. The screw shaft is provided with a shoulder 27 so positioned as to be engaged by the latch 25 when the pinion 15 is meshed with the engine gear 16, and thereby prevent demeshing of the pinion until the rotational speed of the driving clutch member exceeds a predetermined minimum.

20 Means are provided for frictionally transmitting sufficient torque from the pinion to the driving member, while the pinion is overrunning, to gradually accelerate the clutch member, screw shaft, and power shaft to a speed sufficient to release the latch, even though the starting motor (not illustrated) which actuates the power shaft is deenergized. As here shown this is accomplished by means of a sleeve 28 journaled on the driving clutch member 10 and having a flange 29 provided with coupling lugs 31 adapted to engage similar lugs 32 on the driven coupling member 13 so as to cause the sleeve to rotate with the driven coupling member while permitting sufficient longitudinal movement of the latter to disengage the teeth 11, 12 of the overrunning clutch members 10, 13. The driving clutch member 10 is provided with a radial flange 33, and a pair of inter-threaded coil springs 34, 35 are located between the flanges 29, 33 in frictional contact therewith and with each other. A lock ring 36 seated in the coupling member maintains the springs under suitable endwise pressure.

25 In operation, starting with the parts in the positions illustrated in Fig. 1, rotation of the power shaft in the direction of the arrow (a) is transmitted through the spring 6 to the screw shaft 8, causing the driving clutch member and control nut 10 to be traversed to the right. The

pinion 15 is thus moved through the driven clutch member 13 and spring 18 into mesh with the engine gear 16, the meshing movement being limited by engagement of the nut 10 with the ends 31 of the threads on the screw shaft. At this time, the latch 25 drops down behind the shoulder 27 on the screw shaft, thereby preventing demeshing movement of the drive parts.

When the engine fires, the acceleration of the pinion 15 causes it to overrun the power shaft, 10 while the clutch spring 22 yields to allow the teeth of the overrunning clutch members to ratchet over each other as shown in Fig. 2. If it should be a false start, as soon as the power shaft attains corresponding speed with the engine gear, cranking is resumed, the overrunning clutch members being reengaged by the spring 22.

When the engine becomes self-operative, torque is transmitted from the overrunning pinion and clutch member 13 through the sleeve 28, and friction spring members 34, 35 to the barrel 19 and the clutch nut 10. If the starting motor is maintained in operative condition by the operator, this torque assists in accelerating the power shaft 1 to the speed necessary to retract the latch 25 from engagement with the shoulder 27 on the screw shaft, and thus permit the member 10 with its associated parts to be traversed back to idle position. If the starting motor should be immediately deenergized when the engine becomes self-operative, the torque transmitted through the frictional drag connection 34, 35 etc. will gradually accelerate the power shaft to the necessary speed to insure demesh of the pinion 15 from the engine gear 16.

Although but one embodiment of the invention has been shown and described in detail, it will be understood that other embodiments are possible, and that various changes may be made in the design and arrangement of the parts without departing from the spirit of the invention.

I claim:

1. In an engine starter drive a power shaft, a hollow screw shaft journaled thereon, yielding means for connecting the screw shaft for rotation with the power shaft, a pinion slidably journaled on the power shaft, a control nut and driving overrunning clutch member threaded on the

screw shaft, centrifugal latch means resisting longitudinal movement of the control nut on the screw shaft, a driven overrunning clutch member splined on the pinion, a barrel member enclosing the nut and clutch members, a sleeve journaled on the control nut having a flange at one end, said flange and driven overrunning clutch member having coupling means for rotation in unison while permitting relative longitudinal movement, and frictional drag means mounted on the sleeve for transmitting a limited amount of torque from the sleeve to the control nut when the pinion overruns the control nut.

2. An engine starter drive as set forth in claim 1 in which the drag means is in the form of coiled springs having frictional engagement with the sleeve and control nut, and with each other.

3. An engine starter drive as set forth in claim 2 in which the control nut and sleeve have flanges between which the springs are located, and said springs are inter-threaded whereby relative rotation between the springs increases their end-wise pressure against said flange.

4. An engine starter drive as set forth in claim 1 including further a barrel member enclosing the clutch, sleeve and spring members, and means in the barrel yieldingly pressing the clutch members into engagement.

5. In an engine starter drive a power shaft, 30 a pinion slidably journaled on the power shaft for movement into and out of mesh with a gear of an engine to be started, means for traversing and rotating the pinion including an overrunning clutch, centrifugal means for holding the pinion

35 in mesh with the engine gear until the power shaft is rotating above a predetermined speed, and frictional coupling means for transmitting a controlled amount of torque from the pinion to the power shaft when the pinion overruns.

6. An engine starter drive as set forth in claim 5 in which the frictional coupling means comprises a pair of interthreaded springs and means cooperating therewith to rotate the power shaft from the pinion at a speed sufficient to release 45 the centrifugal holding means.
